UNITED STATES PATENT OFFICE.

EDWARD H. COBB, OF WESTMINSTER, SOUTH CAROLINA, ASSIGNOR OF ONE-HALF TO WILLIAM N. COX, OF SAME PLACE.

KEYHOLE-GUARD.

SPECIFICATION forming part of Letters Patent No. 600,304, dated March 8, 1898.

Application filed May 21, 1897. Serial No. 637,560. (No model.)

To all whom it may concern:

Be it known that I, EDWARD H. COBB, residing at Westminster, in the county of Oconee and State of South Carolina, have invented a new and useful Keyhole-Guard, of which the following is a specification.

My invention is in the nature of a keyhole-guard, and has for its object to furnish the trade and the public with a device of this class which shall be cheap and simple in construction, easily operated, easily attached to or detached from a door, and safe and sure when in use.

With this object in view my invention consists in certain details in the construction, arrangement, and combination of the parts, as will be hereinafter described, and afterward specifically pointed out in the claims.

In order that persons skilled in the art to which my invention appertains may be able to construct and use the same, I will now proceed to describe it in detail, having reference to the accompanying drawings, in which—

Figure 1 is a perspective view showing a portion of the outside of a house with a door upon the inside of which my invention has been applied. Fig. 2 is a view in front elevation, representing a portion of the door with my invention applied thereto. Fig. 3 is a similar view illustrating a slightly-modified form of my invention. Fig. 4 is a transverse section on the plane indicated by the line 4-4 of Fig. 2.

Like letters of reference mark the same parts wherever they occur in the various figures of the drawings.

Referring to the drawings by letters, A is a door of any ordinary, well-known, and approved construction.

In Figs. 1 and 2 I have shown a door in which a mortise-lock is inserted, while in Fig. 3 I have shown a door to which the ordinary rim-lock has been attached, said rim-lock being marked A'.

B is a keyhole. (Represented in full lines in Fig. 1 and in dotted lines in Figs. 2 and 3.)

C is a plate pivoted at C' on the inside of the door adjacent to the keyhole, preferably a short distance above it, and provided with a projecting pin C' at its lower end. The central portion of this plate is sufficiently wide

to cover the keyhole and leave some little margin on either side thereof. Beneath this plate, either upon the face of the door or seated in a recess therein, is a spring-piece D, secured by a screw D', and having a projection D² to the right of the plate C, when said plate is in the position shown in full lines in Figs. 2 and 3 and covering the keyhole, which serves to prevent said plate from moving off the keyhole to the right. To the left of the plate C is a projection D³, which may be beveled on the side toward the key, but must be perpendicular on its extreme left-hand side. This projection serves to permit the ready movement of the plate, when desired, to the position shown in dotted lines in Fig. 3, in which position said plate will be secured against the abrupt end of the projection D³. Upon the free end of the plate D is a push-button D⁴, which projects through an opening in a keeper or securing-plate E, attached to the door by means of screws E', the upper one of which in the construction shown in Fig. 3 may be one of the screws for securing the rim-lock to the door. The plate C is prevented from accidentally rising from the spring-plate D by means of a guard F, secured to the door and under which the plate moves, as clearly shown in Figs. 2 and 3. This guard-plate C is normally held in the position shown in full lines in Figs. 2 and 3, in which position the keyhole is covered by a spring G, secured at one end to the plate and at the other end to the door, the securing means being ordinarily a staple G', as in Fig. 3.

H is an elastic bar secured to the door below the keyhole by means of a screw H', passing through a coil in the center of said bar, each end of said bar being provided with a ring or loop, the lower one being marked H² and the upper one H³. A cord or flexible cable I is secured in the lower loop and passes through the staple G² and the staple G', and from thence through the hole J through the door to the outside, where it may be attached to a secret slide or latch (not herein shown) known only to the occupant of the house, whereby the guard-plate C may be operated from the outside. This hole may be protected by a plate or escutcheon, if desired.

The operation of my invention may be described as follows: Assuming the parts to be in the position shown in Fig. 2, with the guard-plate C lying over and effectually covering up the keyhole, it will only be necessary in order to uncover the keyhole from the outside to press the button D⁴, which will depress the spring-plate D and release the guard-plate C of the restraint of the projection D³, when it can be readily pushed to the left into the position shown in dotted lines in Fig. 3, when the keyhole will be uncovered. This adjustment of the guard-plate C to the left may also be accomplished without depressing the spring-plate D by simply pushing the guard-plate to the left, when, by riding over the incline or bevel of the projection D³, it will depress the spring-plate in its passage, and when the abrupt end of the projection D³ is reached the spring-plate will by its own resiliency move outward and spring the projection D³ into position on the right of the guard-plate, thus holding it in its adjusted position and leaving the keyhole uncovered. This operation may be performed from the outside by simply pulling upon the cord from the outside. To spring the guard-plate C back into the position shown in full lines, in which position the keyhole is covered, it is only necessary to release the guard-plate C of the restraint of the projection D³ on the spring-plate D by pressing the button D⁴, when the guard-plate will be moved to the right by means of the spring G.

35 The advantages of my improved keyhole-guard will be obvious from the foregoing description. It will be readily seen that my invention provides absolute security against the insertion of a false key into the lock from the outside as well as the inspection of the contents and the actions of the occupants of the room through the keyhole. At the same time the keyhole may be readily uncovered by persons possessing the right to uncover it,

and the device being extremely cheap and 45 simple may be readily secured upon the door by any ordinary person, not requiring the expensive services of a skilled mechanic.

Having thus fully described my invention, what I claim as new, and desire to secure by 50 Letters Patent, is—

1. In a keyhole-guard the combination with a guard-plate pivoted to the inside of the door in position to cover the keyhole, of a spring-latch secured to the door under the 55 guard-plate and provided with projections to secure the guide-plate in either its operative or inoperative position and a perforated keeper for the free end of said spring-plate, said spring-plate being provided with a push-button projecting from the perforations in said keeper, substantially as set forth.

2. In a keyhole-guard the combination with a guard-plate pivoted to the door in position to cover the keyhole, a spring-plate secured 65 at one end to the door under the guard-plate and provided with a projection having one inclined and one abrupt side and a guard or keeper secured to the door and projecting over the guard-plate to prevent it rising from 70 the door, substantially as set forth.

3. In the keyhole-guard herein described the combination with the guard-plate pivoted to the door, the keeper attached at one end to the door and projecting over the guard-plate, the spring secured to the guard-plate and the door for holding the guard-plate normally in its operative position, the spring-latch secured to the door under the guard-plate, the elastic lever pivoted to the door and 80 attached to the guard-plate at its free end and the cord attached to the opposite end of said lever and passing through the door, substantially as described.

EDWARD H. COBB.
